UNITED STATES PATENT OFFICE.

HUGO S. HASSELQUIST, OF CHICAGO, ILLINOIS, ASSIGNOR, BY MESNE ASSIGNMENTS,
TO AUTOPOINT MANUFACTURING COMPANY, OF CHICAGO, ILLINOIS, A CORPORA-
TION OF ILLINOIS.

PENCIL.

Application filed July 24, 1920. Serial No. 398,765.

To all whom it may concern:

Be it known that I, HUGO S. HASSELQUIST, a citizen of the United States, residing at Chicago, county of Cook and State of Illinois, have invented certain new and useful Improvements in Pencils, of which the following is a specification.

This invention relates to a pencil equipped with propelling mechanism interiorly of its body, and operable by means exteriorly thereof, for advancing into operative position a lead at one end, and an eraser at the other. In many respects the present pencil follows the constructions already disclosed in certain applications of Charles R. Keeran now pending as Serial Nos. 213,241, et al.; it exhibits, however, certain improvements of my own which have to do particularly with details of manufacture and assembly.

It is to be understood, therefore, that the present pencil embodies a number of the features claimed in the applications aforesaid, as well as certain other improvements to which specific reference will hereinafter be made.

In the accompanying drawing an exemplification of this invention is shown in the manner following:

Figure 1 is a longitudinal section through the pencil body which may be formed of some such material as wood, the interior parts being shown in elevation; Fig. 2 is an enlarged longitudinal section through the upper portion of the pencil, the parts interiorly of the body being represented mostly in elevation; and Figs. 3, 4 and 5 are transverse sections taken, respectively, on lines 3—3, 4—4 and 5—5 of Fig. 2.

In the use that is herein made of the terms "upper" and "lower," it should be understood that I am referring to the pencil as it is pointed in use—that is, with the eraser end up, and the writing end down.

In Fig. 1, the pencil body, designated as A, is represented as having a lower end 6 which terminates bluntly in the form of a truncated cone. Arranged within an axial bore in the body is a tube 7 that is deformed throughout its lower portion 8 to present a cross section other than round. As shown in Fig. 5, for example, the deformation of the tube may be such as to provide, in effect, four fluted walls. At its lower extremity 9 this tube may be reduced to fit within a combined ferrule and tip 10, screw threads

being suggested as a convenient means for connecting the one part to the other. By forming the sides of the ferrule to align in flush relation with the tapered walls of the pencil, as shown, a smooth and neat appearance is presented. Within the tip end of the ferrule is an axial bore 11 whose walls are suitably constricted to frictionally engage with a lead B that is projected for use.

Interiorly of the pencil body may be arranged a number of slots 12 disposed radially of the bore containing the tube 7, these slots extending longitudinally of the pencil from its upper end downwardly for a desired distance to constitute chambers in each of which a reserve lead C may be accommodated. Attached to the upper end of the pencil is a cap 13 provided with a central aperture from which radiate slots 14 which are in register with the body slots 12 to thereby preserve open the passage into each reserve lead chamber. Depending from the cap is a circular wall 15, exteriorly threaded, and offset as at 16 to provide a shoulder below which is a lower circular wall 17 which may be interiorly serrated or otherwise formed to fit nonrotatably upon the upper end of the tube 7 extended through its central opening, the extremity of the tube being then upset or spun out, as at 18, to overlie the cap to thereby lock it in place.

The means for propelling a lead through the pencil may be of any suitable kind. As shown in the drawing, it is preferred to use an operating sleeve 19 telescoped within the tube 7 for, perhaps, half its length, the lower end of the sleeve being formed with interior threads 20 which engage with the body of a threaded plunger 21 which is flattened out at one place near its lower end to provide, in effect, a pair of laterally extending fins 22. Under normal operating conditions, the lower end of the plunger is disposed within the deformed portion 8 of the tube, as shown in Fig. 2, wherein the fins act to prevent rotation of the plunger relative thereto. The plunger being free to move longitudinally, but not otherwise, it may be propelled by rotating the operating sleeve 19 through means presently to be described so as to project a lead B, as desired.

through the constricted opening 11 that is formed axially in the tip. Since the exact construction of the parts which constitute the propelling mechanism for the lead is of 5 relatively minor importance to this invention, and may be varied, if desired, further explanation thereof is not deemed essential. The features of improvement that are novel to this invention are associated with 10 the operating sleeve 19 for the purpose of providing a rotating means therefor. Referring now to Fig. 2, I have shown a collar 23 whose lower end is interiorly threaded as at 24 to connect with the cap walls 15, the collar being extended upwardly a desired 15 distance and having an interior annular groove 25 within which may seat a split ring 26 preferably formed of spring material. Arranged to rotate freely upon the 20 collar is a sleeve 27 whose upper end may be inturned as at 28 to frictionally engage with an eraser 29 that is adapted to be received within the sleeve. A means is provided for connecting the collar and eraser 25 sleeve and for establishing rotative continuity between the eraser sleeve and the propelling sleeve, this means comprising a bushing 30 which may be formed with upwardly extending walls 31 that are preferably 30 corrugated or grooved exteriorly, as at 32, so as to engage non-rotatably with the eraser sleeve. In the manufacture of these parts the walls 31 may be initially 35 grooved or corrugated and thereafter be driven to a tight fit within the sleeve, this movement of the one part relative to the other acting to form in the sleeve walls grooves or corrugations that are complementary to those in the bushing. Exteriorly of the bushing is an annular groove 32 adapted to register with the groove 25 that is formed in the collar, the split ring 26 being disposed within both grooves simultaneously. The bushing is further 40 formed with an axial opening 33 within which is received the upper end of the operating sleeve, and a stop for the sleeve is also provided by turning inwardly, as at 45 34, the walls of the bushing adjacent the upper end of its opening. When the parts 50 are formed and related in this manner, the operating sleeve may be permanently connected to the bushing as by means of solder 35 which is applied upon the under side of the bushing, preferably within a slight annular bevel or groove 36, as shown.

According to this invention, the parts 60 may be formed inexpensively and be assembled very expeditiously. The operating sleeve is received within the bushing only to the distance that is determined by the stop 34, following which the soldering operation may be performed to secure these parts immovably together. The bushing may likewise be secured to the sleeve by a drive fit,

as already explained, so that these parts—the eraser sleeve, the bushing, and the operating sleeve—are maintained together in unitary relation. Thereafter they may be assembled upon the collar through the medium of the split ring 26 which provides a freely rotatable, but inseparable, connection. The collar in these circumstances operates merely as a medium for connecting the eraser sleeve, together with its associated parts, to the pencil body.

Within the eraser sleeve may be positioned a plate 37 in abutting relation to the bottom end of the eraser. Whenever desired, the eraser sleeve may be rotated in the direction requisite for propelling the plunger in an upward direction so as to project its upper end against the plate 37 to thereby advance the eraser within its sleeve. In Fig. 2, the upper end of the plunger is shown close to the plate in the position that it would occupy just preliminary to advancing the eraser. It is thus apparent that this construction permits the parts herein described to operate as a means for advancing the eraser, as well as for advancing a lead.

I claim:

1. A pencil having within its body a lead propelling mechanism with which is fixedly associated an operating unit therefor, including a sleeve and collar inseparably connected, the latter stationary upon the body but detachable therefrom, the connection between the sleeve and collar consisting of a bushing arranged interiorly of each and secured in a freely rotatable relation to the collar, the bushing being provided with exterior corrugations adapted to enter grooves formed interiorly of the sleeve when the bushing is forced to a drive fit therewithin, whereby the bushing and sleeve are inseparably interlocked, the bushing being also connected fixedly with the lead propelling mechanism whereby the sleeve may serve as an operating means therefor, substantially as described.

2. A pencil having within its body a lead propelling mechanism with which is fixedly associated an operating unit therefor arranged exteriorly of the pencil body, the operating unit including one rotatable part with which is inseparably connected a collar having a detachable connection with the body, and a connection between the collar and the rotatable part comprising a member formed independently of each having a fast and inseparable connection with the rotatable part and a loose connection with the collar, the latter connection consisting of two grooves one formed in the member and the other in the collar, within both of which is seated a resilient device adapted to connect them in a freely rotatable manner, said member also having a fast and inseparable con-

nection with the lead propelling mechanism, substantially as described.

3. A device having an interior lead propelling mechanism with which is fixedly associated an exterior operating unit comprising a collar and a sleeve arranged end to end in inseparable relation, and a bushing connected inseparably to the collar and sleeve and fast to one and loose to the other, the loose connection consisting of a split ring that is seated partly within each of two registering grooves, one formed in the bushing and the other in the part that is loosely connected therewith, substantially as described.
- 15 4. A pencil having within its body a lead propelling mechanism and exteriorly of its body an operating unit therefor including one rotatable part, and a coupling element for detachably securing the rotatable part to the body by a screw thread connection, the means for securing the coupling element to the rotatable part comprising a member carried by the one and spring pressed into an annular groove that is formed in the other, said means also having an inseparable operating connection with the lead propelling mechanism, substantially as described.
- 25 5. A pencil having in its assembly a lead propelling mechanism with which is fixedly

associated an operating unit which includes 30 a rotatable part and a bushing connected fast and inseparably to said part, loosely to the pencil, and operatively to the lead propelling mechanism, the loose connection consisting of a split ring that is seated partly 35 within each of two registering grooves, one formed in the bushing and the other interiorly of the pencil, substantially as described.

6. A pencil having in its assembly, a lead 40 propelling mechanism with which is fixedly associated an operating unit including a rotatable part, a bushing interiorly thereof having a drive fit therewith such that the one is maintained in non-rotatable and inseparable relation to the other, and means providing a freely rotatable but inseparable connection between the bushing and the pencil, there being also an operative connection between the bushing and the lead propelling 45 mechanism such that the rotatable part may serve as an operating means for the lead propelling mechanism, substantially as described.
